FLEXIBLE STIFFENING ELEMENT FOR
BODY-SUPPORTING GARMENTSCamilla Bachmann née Klee, Hamburg-
Bahrenfeld, GermanyApplication July 11, 1950, Serial No. 173,053
In Germany July 12, 1949

5 Claims. (Cl. 3—260)

1

Bust-bodices with breast-pockets in which formable strengthenings can be put in are well known. Rods of whalebone, steel or Celluloid, elastic stripes or little plates and aluminum-foils are used as stiffening-means. All these linings put a disadvantageous pressure on the breast and become affected by perspiration. Plates of bruised cork, fastened by plastic masses have been proposed, and an aluminum-foil has been laid into the bruised-cork-mass. Nevertheless, the cork-plates during a short period of use become brittle, and therefore, useless, the plate-edges, causing dragmarks.

These disadvantages are overcome by the present invention concerning a bust-bodice with breast-pockets having shapeable stiffenings (German: Verstärkungen). These stiffenings consist of a lining, able to be shaped and inserted in a soft, yielding envelope of natural or artificial caoutchouc. According to a favoured type of the invention in question, the yielding envelope sticks out over the edge of the lining. The lining, too, can be pierced, that is, perforated, the envelope therefore being connected through the holes. According to a further type of the present invention, the stiffening decreases in its thickness towards the edge so that it can be perforated, and the envelope can stick out over the edge of the stiffening's holes.

In the drawing, one type of the invention is illustrated by way of example in which,

Fig. 1 illustrates a lining of perforated aluminum-foil.

Fig. 2 illustrates the complete stiffening-lining (German: Versteifungs einlage), with caoutchouc-envelope.

Fig. 3 is a sectional view in the direction A—B, according to Fig. 2.

Fig. 4 shows a bust-bodice with breast-pockets, in which stiffenings are inserted in the latter.

Fig. 5 is a section, similar to that of Fig. 3, having smoothed or decreasing stiffening at the edges.

Fig. 6 is a section through a perforated stiffening.

Fig. 7 is a section in direction C—D, according to Fig. 6.

An aluminum-foil 1, having holes or slits 2, is inserted in a rubber-mass, in a way that the foil 1 is completely surrounded by the rubber-mass 3, sticking out at the edges with a border of 2 to 5 mm. The rubber-mass consists of soft-rubber, and therefore a soft yielding border 4 is obtained, insertable into the breast-pocket of the bust-bodice in such a manner, that no marked edges

2

can be caused. The upper border 4 fits snugly to the structure of the body, so that the stiffening cannot be perceived from the outside. This new stiffening will prevent undesirable pressure upon the female breast.

Suitably, the rubber-envelope 3 is vulcanized round about the foil 1. Penetrating the perforations 2 of the foil 1, the rubber-mass in fact is unsolvably connected with the foil 1.

10 The decreasing of the foil 1 towards its edges, causing an imperceptible transition into the soft rubber-border 4, as it is seen in Fig. 5, has also turned out to be useful. Instead of aluminum, other metals, like tin can be used for the 15 lining. A tissue or a netting of metal-threads, elastic artificial or natural fibres, or artificial or natural horse-hair of textile-fibres etc., can also be used as a lining. Because the tissue is pervious, the soft rubber-mass penetrating through 20 the cavity, can be connected by vulcanization.

Any pressure or pricking by sharp edges or projecting wires is avoided by the complete insertion of the foils or tissues. In a complete and yielding way, the soft border 4 conforms to the 25 structure of the body. The stiffening linings are laid into the breast-pockets 5 of the bust-bodice 6 (Fig. 4) and the wearer will be able to shape them in any manner to conform to the contour of her breast.

30 In order to obtain proper ventilation the stiffening-lining can, too, be perforated by holes, slits, etc., as illustrated at 7 in Figures 6 and 7. At these stiffenings, too, the envelope 3 protruding at the edges of the holes 7.

35 The stiffenings are unbreakable and therefore longlasting. They don't absorb any moisture and they are washable. They are unobjectionable anatolically and hygienically. Because of certain chemical admixtures, added to the rubber-mass, also by warmth, any rise of caoutchouc-scent will be prevented by means of this special kind of rubber.

I claim:

40 1. A flexible stiffening element adapted to be 45 removably associated with a body supporting garment for stiffening selected portions of said garment, which comprises a flat member formed from flexible non-resilient metal manually deformable and having the characteristic of retaining the shape to which it is deformed embedded in a soft, flexible rubber envelope, said rubber envelope completely surrounding said deformable member throughout its length and being 50 vulcanized thereto, whereby said member is permanently and wholly enclosed in said envelope,

said rubber envelope having a portion extending outwardly beyond the edges of said member to provide a thin peripheral rubber edge around said member.

2. A flexible stiffening element adapted to be 5 removably associated with a body supporting garment for stiffening selected portions of said garment, which comprises a flat member formed from flexible non-resilient metal manually deformable and having the characteristic of retaining the shape to which it is deformed embedded in a soft, flexible rubber envelope, said rubber envelope completely surrounding said deformable member and being vulcanized thereto, whereby said member is permanently and wholly enclosed in said envelope, said rubber element having a portion extending outwardly beyond the edges of said member to provide a thin rubber rim extending continuously around the periphery of said member.

3. A flexible stiffening element adapted to be 10 removably associated with a body supporting garment for stiffening selected portions of said garment, which comprises a flat member formed from flexible manually deformable non-resilient metal embedded in a soft, flexible rubber envelope, said rubber envelope completely surrounding said member and being vulcanized thereto, whereby said member is permanently and wholly enclosed in said envelope, said rubber element having a portion extending laterally outwardly beyond the edges of said member to provide a rubber rim therearound, said rubber rim tapering outwardly to a thin peripheral edge.

4. A flexible stiffening element adapted to be 15 removably associated with a body supporting garment for stiffening selected portions of said garment, which comprises a flat member formed from flexible manually deformable non-resilient metal, said element being of decreasing thickness 20 in the direction of its peripheral edges and being

embedded in a soft, flexible rubber envelope, said rubber envelope completely surrounding said member and being vulcanized thereto, whereby said member is permanently and wholly enclosed in said envelope, said rubber element having a portion extending laterally outwardly beyond the edges of said member to provide a rubber rim therearound, said rubber rim tapering outwardly to a thin peripheral edge.

5. A flexible stiffening element adapted to be 25 removably associated with a body supporting garment for stiffening selected portions of said garment, which comprises a flat perforated member formed from flexible manually deformable non-resilient metal embedded in a soft flexible rubber envelope, said rubber envelope completely surrounding said member and being vulcanized thereto, whereby said member is permanently and wholly enclosed in said envelope, said rubber element having a portion extending laterally outwardly beyond the edges of said member to provide a rubber rim therearound, said rubber rim tapering outwardly to a thin peripheral edge, said rubber envelope having portions extending through the perforations in the deformable element from one side of the rubber envelope to the other.
